UNITED STATES PATENT OFFICE.

THOMAS F. SHIELS AND WILLIS RAY BOLTER, OF LOWELL, MICHIGAN.

PUNCTURE-PROOF INNER CASING FOR PNEUMATIC TIRES.

1,032,955.

Specification of Letters Patent. Patented July 16, 1912.

Application filed November 9, 1911. Serial No. 659,352.

To all whom it may concern:

Be it known that we, THOMAS F. SHIELS and WILLIS RAY BOLTER, citizens of the United States, residing at Lowell, in the county of Kent and State of Michigan, have invented certain new and useful Improvements in Puncture-Proof Inner Casings for Pneumatic Tires; and we do declare the following to be a full, clear, and exact description of the invention, such as will enable others skilled in the art to which it appertains to make and use the same.

This invention relates to improvements in inner casings for pneumatic tires.

One object of the invention is to provide a casing of this character adapted to be placed between the outer and inner tubes of the tire and to be securely held in position to reduce the strain or pressure of the inner tube against the outer tube and to effectually protect the inner tube from puncture.

With this and other objects in view the invention consists of certain novel features of construction, and the combination and arrangement of parts as will be more fully described and claimed.

In the accompanying drawings; Figure 1 is a side view of a portion of a tire having our improved casing applied thereto, parts being broken away to more clearly illustrate the arrangement of the casing. Fig. 2 is a cross sectional view through the tire and casing; Fig. 3 is a sectional perspective view of the improved casing removed from the tire; Fig. 4 is an enlarged plan view of a portion of the casing, parts of the same being broken away and in section to illustrate the construction of the fabric forming the casing; Fig. 5 is an enlarged sectional view of the fabric as shown in Fig. 4.

Referring more particularly to the drawings, 1 denotes the outer tube of the tire and 2 denotes the inner tube. The tubes 1 and 2 may be of the usual or of any desired construction and between the same is arranged our improved shoe or casing 3 formed of a practically puncture proof flexible fabric strip, the edges of which are secured to metallic rings 4 of substantially triangular form in cross section as shown and provided with flat or square inner surfaces 5 brought together in close engagement when the rings are arranged in position for holding the casing. The inner surface of the rings has a slight transverse curvature and

when said rings are brought together these inner sides form a smooth bearing surface for the adjacent side of the inner tube of the tire.

In the outer sides of the rings are formed right angular longitudinal recesses 6 within which are seated the edges of the casing, said edges being firmly secured in the recesses 6 of the rings by screws or rivets 7 as shown. The depth of the recesses 6 corresponds to the thickness of the edges of the casing 3 seated thereon so that when said edges are secured to the rings the outer surfaces thereof will be flush, thus permitting the outer side of the rings and the adjacent outer surface of the casing to closely fit the inner surface of the outer tube of the tire as clearly shown in Fig. 2 of the drawing. When the rings and casing are thus applied to the tires, the casing will form an efficient practical puncture proof covering for the inner tube of the tire and will also relieve the outer tube from strain or pressure by the inner tube when inflated.

The fabric forming the casing 2 comprises outer layers 8 of canvas and an inner canvas layer 9. Between the layers of canvas 8 and 9 are arranged layers 10 of closely woven cane, ratan, or the like between which and the layers of canvas are preferably arranged layers 11 of rubber to which are vulcanized the layers of canvas and cane. The layers of rubber, however, may be dispensed with if desired and the layers of canvas stitched or otherwise firmly secured to the layers of cane or ratan. The casing when formed of fabric constructed as herein shown and described will be strong, durable and practically puncture proof in construction and will be sufficiently flexible or pliable to freely yield with the movement of the tires. The casing has also been found to be frictionless and non-heating.

The fabric while herein shown and described as being arranged to form a casing it is obvious that the fabric may also be embodied in or employed for relining old tires or for forming blow out patches.

From the foregoing description taken in connection with the accompanying drawings, the construction and operation of the invention will be readily understood without requiring a more extended explanation.

Various changes in the form, proportion and the minor details of construction may be resorted to without departing from the

principle or sacrificing any of the advantages of the invention as claimed.

Having thus described our invention, what we claim is;

- 5 1. An inner casing for pneumatic tires comprising a pair of rings having upper edges curved to conform to the inner tube when inflated, and flat closely fitting vertical engaging surfaces, and having in their 10 outer side surfaces right angular notches or recesses, and a strip of flexible puncture proof fabric having its edges secured in the notches of said rings whereby the fabric is flush with said outer side surfaces and is 15 held in position between the inner and outer tubes of the tire, supporting the inflated inner tube.
2. An inner casing for pneumatic tires comprising a puncture proof fabric formed

of an outer layer of canvas, layers of woven cane, an inner layer of canvas and layers of rubber arranged between said layers of canvas and cane, said layers being vulcanized together to form the fabric, and rings having outer angular recesses receiving the 25 edges of the fabric flush with their outer side surfaces the whole adapted to be placed within the outer tube and to receive and support the inner tube to form the complete tire.

In testimony whereof we have hereunto set our hands in presence of two subscribing witnesses.

THOMAS F. SHIELS.
WILLIS RAY BOLTER.
